MACHINE FOR PACKAGING SOFT PRINTED BUTTER

Arthur Perrault, Forest Lake, Minn., assignor, by direct and mesne assignments, to Burch O. Gustafson, White Bear Lake, Minn., and an undivided fractional interest to Ralph L. Dugger, Minneapolis, Minn.

Filed Nov. 18, 1957, Ser. No. 697,102

40 Claims. (Cl. 53—64)

This invention relates generally to butter packaging apparatus and pertains more particularly to an automatic machine for cartoning butter or similar materials into what is commonly termed "Eastern flat packs" where four one quarter pound prints lie side by side.

This invention is adapted for packaging of various soft-printed oleaginous materials of which butter, whipped butter, whipped margarine and the like, which are commonly formed into quarter pound prints, which latter are then wrapped in parchment paper and then packaged. For simplicity in nomenclature such substances are herein, collectively designated "butter."

One important object of the invention is to provide packaging apparatus that is capable of packaging automatically parchment-paper-wrapped prints of soft-printed butter or the like substances, while the prints are still soft. More specifically, an object of the invention is to bend the carton about pre-scored or weakened fold lines in such a manner that little or no force is exerted against the soft butter of the prints itself. Also in this connection the invention provides for transferring the butter from station to station within the machine in such a way that the butter is not subjected to sufficient pressure to compress or distort the printed butter from its original shape.

Another object of the invention is to provide butter packaging equipment that will be relatively fast in its cartoning of the printed butter. In this regard it is within the purview of the invention to feed or advance the butter while certain carton bending operations are taking place. Stated somewhat differently, it is an object of the invention to avoid having certain operations completed before other operations are inaugurated; for instance that the first carton blank bending operation shall take place against a pair of wing members that are inserted into position while the four quarters of printed butter are being fed laterally into the resultant U-shaped configuration of the carton blank formed by the bending operation about such wing members.

Another object is to provide a machine that is operated by a combination of mechanical and pneumatic means, thereby rendering the machine exceptionally compact and of simpler construction than where operated solely by mechanical means.

A further object of the invention is to provide a butter packaging machine that does not depend upon any synchronized feed of the printed butter to its first station, the machine being able to accept quarter pound prints of butter at random.

Still another object of the invention is to provide a machine of the foregoing character that requires a minimum of supervision with respect to its operation, and actually experience has shown that no attendant need remain in the immediate vicinity of the machine in order for the machine to operate in a highly satisfactory and reliable way. Thus the invention contemplates butter packaging apparatus that will be exceptionally rugged and

that will not get out of order easily and will operate with no attention or at the most, only a little attention.

Still another object of the invention is to provide a sensitive protection against mechanical overloads. In this regard it may be stated that in conjunction with the overload protection there is provided certain power compensation features that are activated as needed, to the end that peak mechanical power demands are minimized and the associated protective equipment is set or adjusted appropriately to become operative in the event such peak loads are exceeded. The invention includes power compensation wherein mechanical energy is stored during periods of relatively low power demand and then released precisely when needed, thereby averaging out the load requirements of the machine.

It is also an object of the present invention to provide a highly effective and efficient carton blank feeding mechanism, and more specifically to provide a feed utilizing suction means for picking off carton blanks one at a time from the stack contained in the magazine, and misfeeding of several blanks simultaneously is virtually precluded.

Other and further objects are those inherent in the invention herein illustrated and described and will be apparent as the description proceeds.

To the accomplishment of the foregoing and related ends, this invention then comprises the features herein-after fully described and specifically pointed out in the claims, the following description setting forth in detail, certain embodiments of the invention, these being indicative however, of but a few of the various ways in which the principles of the invention may be employed. The invention is illustrated in the drawings in which the same numerals refer to corresponding parts and in which:

Figure 1 is a plan view of preferred apparatus that has been selected to exemplify the instant invention;

Figure 2 is a side elevational view of the machine on a somewhat smaller scale than the scale employed in laying out Figure 1;

Figure 3 is another side elevational view, the view being from the side of the machine lying opposite the side from which Figure 2 has been prepared;

Figure 4 is a sectional view taken in the direction of line 4—4 of Figure 3, the view being intended primarily to show most of the cam shafts that provide for the proper synchronized operation of the apparatus;

Figure 5 is a sectional view taken in the direction of line 5—5 of Figure 1, the view being designed to show with considerable particularity the orientation of the various parts constituting the feeding mechanism, although portions of the butter packaging apparatus lying adjacent the feeding mechanism are also pictured;

Figure 6 is a sectional view taken in the direction of line 6—6 of both Figures 1 and 3, this view here again being intended principally to show the details of the feeding mechanism;

Figure 7 is a sectional detail view that would be considered to be taken in the direction of line 7—7 of Figure 5, the view showing a somewhat modified guiding arrangement from that which is actually used in the illustrative embodiment;

Figure 8 is a plan view of a standard Eastern flatpack carton blank, which the present machine is designed to handle;

Figure 9 is a view of an airplane Eastern flatpack carton blank, this view depicting a carton blank that is intended to traverse the guiding arrangement set forth in Figure 7 and which carton blank appears in almost completely assembled form in Figure 26;

Figure 10 is an enlarged sectional view taken in the direction of line 10—10 of Figure 6, the view showing

a pair of curved horns in the process of performing a bending operation about certain pre-scored lines without the printed butter being in contact with any portion of said carton blank;

Figure 11 is a view generally similar to Figure 10 but with the pusher frame in its foremost position and having advanced the butter and its associated carton blank to a more advanced stage of the cartoning operation;

Figure 12 is a view corresponding to Figure 11 but with the pusher frame retracted and certain rear wall section bending fingers in the process of completing their particular operation;

Figure 13 is a sectional view taken generally along the irregular line 13—13 of Figure 12 in order to picture more plainly the butter advancing mechanism that is to progress the butter to the next station beyond that station depicted in Figure 12;

Figure 14 is a view generally similar to Figure 12 but showing a slightly more advanced stage of the operation, the advancing mechanism having moved somewhat forward toward the finish end of the machine than it appears in said Figure 12;

Figure 15 is a fragmentary side elevation showing the advancing mechanism in a position where the sides of the carton are folded;

Figure 16 is a view taken generally in the direction of line 16—16 of both Figures 1 and 3 for the purpose of illustrating the side bending procedure;

Figure 17 is a right hand or end view of Figures 1, 2 and 3 for the purpose of illustrating the carton bending mechanism which accepts the completed or filled cartons, upends them, and pushes them off to one side of the machine for ultimate crating and shipping;

Figure 18 is principally an electrical schematic diagram of the invention, only a few mechanical parts appearing in this view for the general purpose of orienting the electrical features with some of the mechanical details;

Figure 19 is a detailed perspective view showing the carton blank in position for its first bending operation;

Figure 20 is a perspective view illustrating the first carton bending operation;

Figure 21 is a side elevational detail showing the carton blank in a fully bent condition, Figure 20 having shown the carton blank in only a partially bent condition;

Figure 22 is another perspective detail picturing the end sections of the carton blank being bent so as to form the rear wall of the completed carton;

Figure 23 is another perspective detail, this view showing the bending of flap portions attached to the side wall sections of the carton blank;

Figure 24 is a view showing a successive step constituting the bending in of tabs located on each side of the carton blanks;

Figure 25 is a perspective showing the next operational step, this view illustrating how the side sections together with their attached flaps are bent into position;

Figure 26 corresponds precisely to Figure 25 but illustrates how the machine will be modified to carry out the step pictured in Figure 25 with the airplane type of carton blank illustrated in Figure 9, this being in contradistinction to the standard type of blank appearing in Figure 8; and

Figure 27 is a perspective view showing the butter in its fully wrapped or fully cartoned state.

Referring now in detail to the drawings, the butter packaging apparatus comprises a generally rectangular frame assembly denoted in its entirety by the reference numeral 20. The frame assembly 20 need not be described in any great detail other than to point out that it includes a lower level 22, an intermediate level 24, and an upper level 26. Supported at the lower level 22 is a first motor 28 drivingly connected to a compressor 30. The compressor is connected to a compressed air

tank 32 which supplies air under pressure to various air cylinders that will hereinafter be dealt with. It might be explained at this time, though, that the intake of the compressor 30 furnishes a vacuum for subsequently to be described suction cups incorporated into the carton blank feeding mechanism.

A second motor 34 is also disposed at the lower level 22, this motor being directly coupled to a set of reduction gears 36. On the output shaft 38 (Figure 4) belonging to the set of reduction gears 36 is mounted for rotation therewith a sprocket 40, the sprocket having entrained thereover a chain 42 (Figures 2 and 3) leading upwardly to a sprocket 44 at the upper level 26. The sprocket 44 is drivingly connected to a conveyor 46 composed of a plurality of articulated sections 48 (Figures 1 and 18). The function of the conveyor is to receive the various quarter pound prints of butter and convey them to a first station where four of these butter prints are then advanced through the machine for the cartoning operation. Four prints in the process of being packaged appear in Figures 10, 11, 12, 14 and 21, and have been collectively assigned the reference numeral 49. As the description progresses, the fact that the conveyor 46 can receive the printed butter in a random fashion will be appreciated, for provision is made for making certain that no more than four quarter-pound prints are delivered to a position confronting the carton blank after it has been fed downwardly into a given position from the subsequently to be referred to feeding mechanism.

For the purpose of protecting the butter packaging apparatus from excessive overload there is employed a compound ratchet and overload clutch mechanism designated by the numeral 50 (Figure 4). This mechanism 50 includes a ratchet 52 mounted on the gear shaft 38 for rotation therewith. Cooperable with the ratchet 52 is a pawl 54 carried on a hub and integral collar 56, the pawl being pivotally connected to said collar 56 by a pivot pin 58. There is a dog 60 integral with the pawl 54 and it is engageable with a pivotal latch arm 62 (see Figure 3) equipped with a catch 64. By reason of a spring 66 the pivotal latch arm 62 is normally projected into an interfering relation with the dog 60 on the pawl. However, there is a solenoid 68 for retracting the latch arm 62 during predetermined periods of operation.

Continuing with the description of the overload and drive mechanism, attention is now directed to an overload gear clutch composed of gear sections 70 and 72, there being a spring 73 for normally urging the section 72 into engagement with the section 70. A narrow groove 74 is disposed on the gear section 72 of the overload clutch and a motor trip arm 76 has one end riding in this groove 74. The motor trip arm 76 is mounted so that its opposite end is operatively associated with a trip switch 78. At this time all that is necessary for a basic understanding of the invention is to know that the trip switch 78 is connected in circuit with the second or drive motor 34.

The clutch section 72 drives a driven shaft 80 which has mounted thereon a sprocket 82 over which is entrained a chain 84 (Figure 2) leading upwardly to a sprocket 86 at the intermediate level 24. The sprocket 86 is mounted directly on what will be termed an air valve actuating cam shaft 88. However the specific function of the cam shaft 88 is better reserved for explanation hereinafter when the various air valves are described.

In addition to driving the sprocket 86 the horizontal shaft 80 also rotates a bevel gear 90 (Figures 2 and 4), the bevel gear 90 being at the lower end of said shaft 80. The bevel gear 90 is in mesh with a driven bevel gear 92 at the lower end of a vertical shaft 94. At the upper end of the shaft 94 is a cam 96 (Figures 1 and 18) which engages the short arm of a bell crank 98 which is slotted at its free extremity so as to be engageable with a pin on the underside of a pusher frame 100 constrained for reciprocal movement in a transverse direction. The

pusher frame 100 carries a head 102 that has a width substantially equal to the combined width of four one quarter pound prints 49.

It might be explained by way of a quick review at this time that the pusher frame 100, together with its particular actuating means, comprises what may be termed a first transfer means. This first transfer means advances printed butter to the first work station where the initial carton blank bending operation takes place.

When actuated, the pusher frame 100 sweeps over a platform 104 at the upper level 26. This platform 104 (see Figure 10) is provided with an upstanding backstop 106 supporting a switch 108. The switch 108 can only be closed initially when the four one quarter pound prints have been deposited onto the platform 104 from the conveyor 46. However, once the pusher frame 100 has been advanced toward the opposite side of the machine its adjacent side will maintain the switch 108 in a closed position. The operation of the switch 108 will become more apparent as the description proceeds, especially when the contents of Figure 18 are discussed. Solely as an introduction though, it can be said at this time that the switch 108 energizes the solenoid 68 so as to permit the pawl 54 to engage its ratchet 52.

Inasmuch as the proper feeding of carton blanks is of the utmost importance to the operation of a butter packaging machine, such as that with which we are now dealing, attention is at this time directed to the carton blank feeding mechanism designated here in its entirety by the reference numeral 110. Such mechanism is most clearly set forth in Figures 5 and 6. From these figures it will be discerned that the feeding mechanism comprises a pair of side plates 112. Also it will be seen that there is a magazine 114 for containing a relatively large number of carton blanks 116. These carton blanks appear in only phantom outline in Figures 5 and 6, but reference may be had to Figures 8 and 9 for two specific types of carton blanks that might be utilized and which are there presented in more detail. For the most part, though, only the carton blank pictured in Figure 8 will be referred to throughout the remainder of this description, the apparatus exemplified being especially adapted to the handling of this particular type of blank.

Continuing with the description of the carton blank feeding mechanism 110, it is to be noted that these carton blanks rest upon a pair of blank supporting tracks 118 equipped with small upstanding dogs 120 at their lower or discharge end. Also notice is to be taken of the presence of side guides 122 which suffice for guiding the carton blanks of the type pictured in Figure 8. Specific reference should be made to Figure 7 where a triangular centrally disposed guide 124 is illustrated for the express purpose of guiding the airplane type of carton blank depicted in Figure 9. Through the combination of side guides 122 and the single triangular guide 124 the machine is rendered more versatile as to the handling of both types of carton blanks set forth in Figures 8 and 9. When using the carton blank of Figure 8, the triangular guide 124 may be removed or the blank notched as is the blank of Figure 9.

As best observed in Figure 5, there is a wheeled pusher 126 provided with a pair of upright strips 128 that engage the rearmost carton blank. Through the media of a biased cord 130 passing over a first sheave or pulley 132 and a second such pulley 134 together with a bias spring 136 (Figure 6), the wheeled pusher 126 is constantly urged in a direction so as to provide a preferred amount of pressurized action against the stack of carton blanks contained in the magazine 114. This can be clearly seen from an inspection of Figure 5.

There is a bracket 138 for engaging the upper end of the foremost blank and it is against this bracket the biasing action of the pusher 126 is applied. The bracket 138 is fixedly located on a cross piece 140 extending between the side plates 112.

Next, attention is called to the presence of a pair of suction cups 142 supported on a cross head or cross piece 144. The cross head 144 is suspended in swing-like fashion by a pair of telescoping arms 145 comprised of a first section 146 and a second section 147. It will be appreciated that the first section 146 is directly attached to the cross head 144 and is movable within the cylindrically configured second section 147. The upper ends of the second section 147 are clamped to a rock bar 148. The rock bar 148 is provided with a crank arm 150. In each side plate 112 is a pivot pin 152 about which a pair of L-shaped rocker arms 154 can rock in actuating the crank arm 150 and hence the rock bar 148. The rocker arm 154 is cam actuated and the cam for performing the actuating function is designated by the numeral 156. The cam 156, as are other cams later to be described, is mounted on a cam shaft 158 which is journaled in the side plates 112.

Whereas the rock bar 148 causes a swinging of the suction cups 142, there is a lift bar 160, this bar being oriented in a vertical direction for raising and lowering the cross head 144 and hence the suction cups 142. It will be observed that the upper end 162 of this second bar 160 is slotted so that it straddles a roller support bar 164. The roller support bar is supported at its opposite ends by the side plates 112. Rotatably mounted on the roller support bar 164 is a pair of rollers 166 which engage the foremost carton blank as can readily be seen from Figure 5. The lower end of the second lifter bar 160 is slotted at 168 and is thereby formed so that it can slidably engage the cam shaft 158. This previously mentioned cam shaft 158 carries a cam 172 thereon for urging the second lift bar 160 downwardly. A spring 174 extending between the bar 160 and the bracket 138 biases the bar 160 upwardly so as to maintain engagement with the cam 172. The lift bar 160 carries a slotted bearing 176 (Figure 5) so as to be movable therewith as a result of the cam action, the slotted bearing having engagement with the cross head 144. In this way the cross head, together with the suction cups 142, is constrained to follow the action of the cam 172 as modified by the action of the rocker arm 154 so as to impart somewhat of an inverted L-shaped travel to the suction cups 142. This movement provides a ready disengagement of the lower edge of each foremost carton blank from the dogs 120 located at the lower end of the blank supporting tracks 118.

Close inspection of Figure 5 will also reveal the presence of an ejector foot 178 fixedly disposed on the slotted bearing 176. Thus when the suction cups 142 are instrumental in peeling off the foremost carton blank 116 with the aforesaid movement there will be a point after the suction cups have been moved downwardly that complete disengagement of this particular blank will be necessary and this is the function of the ejector foot 178. In this regard it is believed readily apparent that there is relative movement of the suction cups 142 with respect to the ejector foot.

Also carried on the cam shaft 158 is a pair of mutilated feed rollers 180 provided with relatively small gripping teeth 182. Of course the movement of the suction cups 142 is synchronized so that the gripping teeth 182 will be in position to engage the lower end of the carton blank as it is ejected from said suction cups.

From Figure 6 it can be seen that there is a vacuum valve 184 connected directly to the intake of the compressor 30, by a tube 185 leading from said valve to said intake. By reason of a vacuum initiating cam 186 also mounted on the cam shaft 158 the vacuum valve 184 is actuated to open position so as to apply vacuum to the suction cups 142 during that portion of their travel when they are dislodging a carton blank 116 from the magazine 114.

One refinement that is worthy of mention is the exist-

ence of a pivoted feeler 188 for sensing whether there is a blank remaining in the magazine 114. This feeler 188 operates a switch 190 in circuit with the drive motor 34. Since there is a slight interval or spacing between carton blanks as they are fed downwardly, provision is made for preventing the stopping of the motor 34 during such an interval. To accomplish this particular purpose an interval cam 192 is also carried on the cam shaft 158, the cam 192 engaging a switch 194 which electrically parallels the switch 190 (see also Figure 18). Of course the switch 194 is only closed during that period when the feeler 188 would be permitted to flex in a direction to open the switch 190 solely by reason of the spacing between vertically fed carton blanks.

A pair of upper reaction rollers 196 bear against the opposite side of the carton blank from that which is engaged by the mutilated feed rollers 180, a lower pair of reaction rollers 198 are also utilized. Both pairs of reaction rollers are preferably of rubber or some other resilient material and are spring biased so as to make a firm engagement with the various carton blanks as they are fed downwardly.

Next to be described is the drive for the cam shaft 158. In furtherance of this particular aim another sprocket 200 is mounted directly on the valve cam shaft 88 that has already been referred to (Figures 2 and 4). This second sprocket 200 is engaged with a chain 202 that passes over a sprocket 204 (Figure 4) on a cam shaft 206. Since the cams carried by the shaft 206 have not as yet been described, the reason for having the cam shaft 206 is not at this time clear, of course, but will be made so hereinafter. A drive gear 208 is carried at the opposite end of the cam shaft 206 and is in mesh with a driven gear 210 on one end of a transverse shaft 212. On the other end of the shaft 212 is a sprocket 214 in engagement with a chain 216 passing about a sprocket 218 located on the cam shaft 158. Consequently, by reason of the various chains involved it will be appreciated that the feeding mechanism 110 is actuated in precise synchronism with the earlier mentioned assemblage of parts.

As can be readily seen from both Figures 5 and 6, there is provided a pair of L-shaped guide members 220 having vertical legs 222 and horizontal legs 224. More will be said later on concerning the function of the horizontal legs 224. Also there is employed a lower L-shaped guide member 226 having a vertical leg 228 and a horizontal leg 230 formed with a slot 232 (Figure 12). Here again, as mentioned above with respect to the horizontal leg 224, the specific function of this last mentioned horizontal leg 230 will be dealt with more fully later on. Although not included in Figures 5 and 6, nonetheless a pair of L-shaped feet 234 appear in Figures 10, 11 and 12. The role performed by these L-shaped feet is to position each carton blank 116 at the proper elevation for its first bending operation.

Up to this point only a brief mention has been made of the two different carton blanks appearing in Figures 8 and 9. Inasmuch as the description is about to concern itself with the first bending operation it is felt that a detailed reference to the exemplified carton blanks will be helpful in following the ensuing description. Accordingly, reference will be first made to Figure 8 where an Eastern flatpack type of carton blank 116-a is set forth. This blank 116-a is provided with a number of pre-scored or weakened fold lines which define various panels and flaps. First of all, reference will be made to what becomes a front wall 234-a, this wall having oppositely issuing tabs 236-a. The front wall 234-a adjoins a top panel 238-a and a bottom panel 240-a. The top panel 238-a is in turn provided with a left side wall 242-a equipped with an integral flap 244-a. Similarly the bottom panel 240-a has adjoined thereto a right side wall 246-a to which is integrally attached a flap 248-a. A pair of rear wall sections

250-a and 252-a are connected respectively to the panels 238-a and 240-a, these rear wall sections ultimately overlapping each other to form a rear wall in the completed carton. The section 250-a is provided with oppositely issuing tucks or tabs 254-a, whereas the section 252-a has only a single tab 256-a.

Referring now in particular to the airplane type of blank labeled 116-b appearing in Figure 9 it may be explained at the outset that this blank is basically similar to the one that is described in the preceding paragraph. Because of the basic similarity those panels performing equivalent functions in the assembled carton bear the same reference numeral but instead of the suffix "a" there is employed the suffix "b." Thus it will be discerned that the side 246-b is attached to the bottom panel 240-b. In this way the sides 242-b and 246-b form wings and are responsible for giving the blank 116-b the airplane appearance it possesses. It will also be observed that the rear wall section 252-b is equipped with a pair of oppositely extending tabs 256-b whereas the blank 116-a is provided with only a single such tab. Another difference resides in the fact that the section 250-b does not have any tabs corresponding to the tabs 254-a issuing from the section 250-a. It is actually because of the absence of any tabs corresponding to the tabs 254-a that the side guides 122 would be ineffectual for properly guiding the blanks 116-b. However, in order to make the machine as versatile as possible without having to resort to any mechanical reorientation of parts, a notch 258-b is cut in the section 250-b. From Figure 7 it will be perceived that this notch 258-b rides on the triangular guide, thus it will be appreciated that the magazine is designed to handle either the blank 116-a or the blank 116-b. However, as will be more readily understood when a subsequent portion of the machine is described, a certain modification thereof must be effected in order to form a complete carton from the blank 116-b.

As more clearly seen from Figures 19 and 20, although such feature now to be referred to appears in other figures, a pair of rectangular wings 270 are located at the first work station on the upper level 26. These wings 270 have a height substantially equal to the height of the front wall 234-a, the purpose of the wings being to confront this particular portion of the blank 116-a. To actuate the rectangular wings inwardly toward each other there is employed a pair of air cylinders 272 which receive air under pressure from an air valve 274 at the intermediate level 24. The air valve 274 is opened by means of a rocker arm 276 pivotal about an intermediate pivot 278 by reason of a cam 280 mounted on the previously referred to cam shaft 88. Owing to the manner in which the cam shaft 88 is driven, as hereinbefore mentioned, it will be recognized that the rectangular wings 270 are actuated inwardly toward each other at the proper time.

Attention is now directed to Figures 5 and 10 where a pair of upper and lower curved horns 282-a and 282-b respectively appear. These horns 282-a and 282-b are mounted on upper and lower rock shafts 284-a and 284-b. For actuating the rock shaft 284-a and 284-b are rocker arms 286-a and 286-b. Also carried on the lower rock shaft 284-b is a take-off arm 288. Providing a connection between the take-off arm 288 and the upper rocker arm 286-a is a connecting link labeled 290. Instrumental in providing the actuating force for the preceding mechanism is a cam 292 (Figure 4) mounted on the cam shaft 206. It will be recalled that the cam shaft 206 was previously mentioned and at that time it was stated that the cams associated therewith would be referred to later on; thus cam 292 is the first cam on this particular shaft to be mentioned. A follower arm 294 is pivotally attached to the intermediate level 24 at its lower end and has an intermediate portion thereof riding against cam 292. Further, there is a link 296 connecting the follower arm 294 to the rocker arm 286-b so as to transmit the necessary motion to the upper and lower

curved horns 282-a and 282-b. It might be explained at this point that the cam 292 is synchronized with the cam 96 so that the horns 282-a and 282-b start their bending strokes at approximately the same time that the pusher 100 is moved transversely. Reference to this feature is made at this particular time only to emphasize that the four quarters of printed butter need not be juxtaposed in confronting relation with the front wall 234-a of the carton blank 116-a prior to the inauguration of a bending stroke performed by said horns 282-a and 282-b.

Reference will now be made to a second pusher frame 298 and the manner in which it is constrained for longitudinal reciprocal movement. It will be noted that this pusher frame 298 is provided with a head 300 that engages the butter so as to advance the butter 49 after the bending operation performed by the horns 282-a and 282-b. Of course, by the time that the pusher frame 298 starts forward, the wings 270 will have been retracted so as to offer no interference with the advancement of the butter. The mechanism for actuating the pusher frame 298 to accomplish the above referred to butter advancement comprises a bell crank 302 slotted at its upper end so as to engage the frame 298. The bell crank 302 is pivoted at its elbow to the middle level 24 of the frame, the pivot point having been indicated in Figure 3 by the numeral 303. On the cam shaft 88 is a cam 304 which engages the short leg of the bell crank so as to move it in a direction that will advance the pusher frame 298 and the butter that is ahead of said frame. Thus while the pusher frame 100 forms a part of what was termed as a first transfer means, the structure described in this paragraph constitutes a second transfer means for advancing the now partially cartoned butter from the first work station to the second work station.

At this stage of the overall functioning of the butter packaging machine the four prints of butter 49 are resting on a platform 306 at the first work station which, of course, could be a mere continuation or extension of the earlier referred to platform 104. It will now be apparent that the horizontal legs 224 and 230 are spaced in a vertical manner so as to accommodate the butter and its now substantially U-shaped carton blanks therebetween, the carton blank itself being supported on the legs 230 during their transfer step. At the same elevation as the horizontal legs 230 is a pair of spaced tracks 308 having a slot 310 therebetween, the slot 310 actually forming a continuation of slot 232. The carton blank 116-a is retained in its substantially U-shaped configuration by means of a presser plate 312, this presser plate forming a general continuation of the horizontal legs 224 of the L-shaped guide 220. The presser plate is biased in a yieldable manner by a pair of coiled springs 314. Support for the presser plate 312 is provided in the form of a fixedly disposed support bar 316. The second work station to which the butter has been advanced is set forth in Figures 11 and 12, Figure 11 illustrating the state of cartoning at the moment that the butter reaches this particular station and Figure 12 depicting a somewhat more progressed state of cartoning.

While at the second station pictured in Figures 11 and 12 there is a flap forming operation that occurs. The particular flaps to be advanced at this particular stage are the flaps 244-a and 248-a. Thus while the flaps 244-a and 248-a reside in substantially parallel horizontal planes at this particular stage of cartoning it is necessary to bend these flaps into a vertical relationship with the sections 244-a and 246-a respectively. To accomplish this aim a pair of fixed forming plates 320-a and 320-b are provided. Cooperable with the forming plates 320-a and 320-b are movable forming members 322-a and 322-b, these forming members having outwardly flared portions as are clearly visible in Figure 13. Respective air cylinders 324-a and 324-b serve to provide the actuating force for moving the members 322-a and 322-b, these cylinders receiving air through tubes 326.

connected to an air valve 328 located at the intermediate level 26. As with the earlier referred to air valve, the air valve 328 is actuated to open position by means of a rocker arm 330 which has riding engagement with a cam 332 mounted on the cam shaft 88. It will be understood that the forming mechanism just referred to is responsible only for bending the flaps 244-a and 248-a, leaving the side wall sections 242-a and 246-a in their original horizontal plane. Subsequently referred to mechanism will cause the proper bending of the sections 242-a and 246-a.

Specific attention is now drawn to the rear wall sections 250-a and 252-a. For bending the lower rear wall section 252-a upwardly is a pair of lower pivotal fingers 340 carried on a pivot shaft 342. An arm 344 extends from the shaft 342 and is pivotally connected to a generally horizontal link 346 at one end thereof, the link being in turn pivotally connected to a lever arm 348. There is a bracket 350 fixed to the intermediate level 24 of the frame 20 to which the lever arm is pivotally connected intermediate its end at a locus 352. The lower end of the arm 348 bears against a cam 354 on the cam shaft 206.

While the above paragraph is concerned with the bending of the section 252-a upwardly the mechanism presently to be described deals with the bending of the section 250-a downwardly. In furtherance of this particular aim, that is bending of the section 250-a downwardly, there is provided a pair of upper pivotal fingers 358 carried on a pivot shaft 360. The pivot shaft 360 is provided with an arm 362 to which is pivotally attached a connecting link 364 extending to a lever arm 366. The lever arm 366 is supported on a downwardly projecting bracket 368 mounted on the frame at its upper level 26. The bracket 368 thus furnishes a pivot point at 370 for the lever arm 366. As with the lower pivotal fingers 340 the upper pivotal fingers 358 are actuated by a cam on the cam shaft 206, the cam in the present instance being denoted by the reference numeral 372. Close inspection of the cam 372 would reveal that it is contoured with a dwell period (not shown), the purpose of which is to provide a pause in the movement of the fingers 358 during a particular portion of the return travel of the fingers 340. However, this will become more apparent and more easily understood hereinafter when a detailed operational sequence is described.

It now becomes clear that in order to progress the butter together with its carton blank from the second station in which the butter appears in Figure 12 to the third work station that some means must be provided for doing so. This means takes the form of a butter transport or advancing mechanism designated in its entirety by the numeral 380. This mechanism 380 includes a carriage 382 having a downwardly extending yoke or cradle 384 (Figure 13). Also from Figure 13 can be seen a plurality of laterally extending wheels 386 that are mounted at either side of the yoke or cradle 384. These wheels 386 ride in fixed channeled tracks 388. The channeled tracks 388 are fixedly disposed relative to the frame 20.

Continuing with the description of the transport mechanism 380 it will now be pointed out that there is an elevator frame 390 having downwardly extending side plates 392 equipped with a plurality of wheels 394. These wheels 394 ride in a pair of grooves formed in the sides of the cradle 384. Owing to the number of wheels 394, that is four such wheels, the elevator frame 390 is constrained for vertical movement only with respect to the carriage 382.

The elevator frame 390 is equipped with a plurality of upstanding lugs 398, there actually being three at each end of the elevator frame. The aft lugs serve to advance the partially cartoned butter whereas the fore lugs serve to advance the preceding completed carton. Of course these upstanding lugs 398 are of sufficient height so as to extend above the slotted legs 230 and the

spaced tracks 308 when the elevator frame 390 is in a raised position.

Provision is made for raising the elevator frame 390 and to accomplish this end an air cylinder 399 is fixedly located on the cross portion of the yoke or cradle 384. A flexible hose 400 connects the air cylinder 399 to an air valve 402 located at the intermediate level 24. A rocker arm 404 is pivotally mounted between its ends at a pivot point 406 and is actuated by a cam 408 on the cam shaft 88.

With reference now to the means for moving the transport or advancing mechanism 380 longitudinally between the second and third stations it will be observed that the carriage 382 has one end of a draw bar link 410 pivotally attached thereto. The opposite end of the draw bar link 410 is pivotally connected to one arm of a bell crank 412, the shorter arm of the bell crank being in turn pivotally connected to an under-slung rock shaft 414 at the intermediate level 24. From the drawings it can be discerned that the reference numeral 416 has been assigned to the generally vertical arm of the valve crank which connects with the draw bar link 410 and the numeral 418 has been given to the generally horizontal arm which rides against a cam 420 mounted on a cam shaft 422.

The drive for the cam shaft 422 will now be described. In the accomplishment of this particular objective a sprocket 424 is attached to the cam shaft 422 and has entrained thereover a chain 426 which is driven by a sprocket 428 located on the shaft 206. It will be recognized that the shaft 206 is the previously mentioned shaft having at one end the gear 208.

While the transport or advancing mechanism 380 is capable of advancing the partially completed carton to the next or third station it will be recalled that the flap forming structure comprised of the movable forming members 322-a, and 322-b and the cooperable fixed forming plates 320-a and 320-b were influential in effecting the bending of the flaps 244-a and 248-a into vertical planes. The vertical relationship of these flaps 244-a and 248-a must be maintained during the advancement to the next station, and it is with the particular means by which this is accomplished that we will now consider. In furtherance of this specific aim it is to be pointed out that the downwardly extending cradle 384 is equipped with laterally projecting rollers 430. These rollers 430 are engageable with a pair of deflector arms 432, pivot pins 434 rendering the deflector arm pivotal about a horizontal axis. These pivot pins 434 are situated in the earlier referred to brackets 350. Also associated with the pivot pins 434 are a pair of transfer arms 436 which are actually attached to the pivot pins so as to be movable in unison with the pivot pins as they are in turn rotated by said deflector arms 432. At the upper extremities of the transfer arm 436 are pickup plates 438, these pickup plates merely engaging the respective flaps 244-a and 248-a so that the inherent resiliency thereof will not permit the flaps to deflect from the parallel vertical plane that they have previously been bent into by the forming members 322-a and 322-b. The motivating force for urging the transfer arm 436, and hence the pickup plates 438, in a transfer or advancing direction is provided by a pair of coil springs 440. In this way owing to the tilt of the deflector arms 432 the continued advancement of the drag mechanism 380 will permit the transfer arm 436 to be moved under the influence of said springs 440. However on the return of the drag mechanism the laterally projecting rollers 430 will cam against the deflector arms 432 so as to move the transfer arms 436 back to their original position so that they will be ready for "picking up" the flaps 244-a and 248-a of the succeeding carton that comes along. The point to be clearly understood at this time, however, is that the pickup plates 438 move in unison with the drag mechanism 380 until the rollers 430 disengage the deflector arms. However by the time that the rollers 430 disengage the de-

flector arms the pickup plates 438 will have been advanced sufficiently so that the required vertical relation of the flaps 244-a, and 248-a is maintained. Notches on the pickup plates 438 see to it that the partially cartoned butter reaches its third work station without the flaps 244-a and 248-a springing outward due to their inherent resiliency.

Participating in the next sequence of events, which events occur at this third station, is a pair of upper and lower tuck-in fingers 450-a and 450-b, these tuck-in fingers having carton squeezing portions 451 thereon. While the office of the carton squeezing portions 451 will be made manifest hereinafter, at this time it will be mentioned, however, that the tuck-in fingers 450-a and 450-b act to bend the various tabs 236-a, 254-a and 256-a into parallelism with the ends of the foremost and rearmost prints of butter. In order to do this, the tuck-in fingers 450-a and 450-b are supported on upper and lower shafts 452-a and 452-b; the tuck-in shafts being in turn journaled in upper and lower brackets 454-a and 454-b, respectively. From Figure 14 it can be seen that actuating arms 456 are integrally supported on the upper shafts 452-a. Links 458 are connected at one end to the actuating arms 456. The other end of these links 458 are pivotally connected to a lever arm 460. The lever arm 460 is in turn supported on an upper pivot shaft 462-a. The shaft 462-a has an arm 464-a extending therefrom and has its extremity pivotally connected to a vertical connecting link 466 with similar articulative linkage associated with the shaft 452-b, including an arm 454-b on a shaft 452-b. Another vertical link 477 is pivotally connected at its upper end to the link 466 and has its lower end pivotally connected to the free end of a rocker arm 468 mounted for arcuate movement about a pivot point 470 located slightly above the shaft 422 but substantially at the intermediate level 24. Actually the rocker arm 464 assumes the form of a bell crank and has its other leg engageable with a cam 482 mounted on the cam shaft 422. This cam shaft 422 is the same shaft that the cam for advancing the transport mechanism 380 is mounted on. Although all of the activating linkage for the shaft 452-b has not been described in detail, it will be understood that the shafts 452-a and 452-b are operated in unison so as to in turn cause concerted movement of the tuck-in fingers 450-a and 450-b.

Only a brief allusion was made to the carton squeezing portion 451 on the tuck-in fingers 450-a and 450-b. While more will be said later on concerning the functioning of these squeezing portions it might be pointed out at this time that the tuck-in fingers 450-a and 450-b are moved sufficiently so that the portions 451, which are somewhat inset, engage the forward wall 234-a and the rear wall composed of the sections 250-a and 252-a with sufficient pressure so as to flex the top panel 238-a slightly upwardly, as best viewed in Figure 24, and the bottom panel 240 downwardly. It will be appreciated that this action facilitates the insertion of the flaps 244-a and 248-a.

Having conditioned the blank to the extent outlined above reference will now be made to a pair of what will be termed curved radius flap lead or guide elements 490-a and 490-b. These elements comprise three curved fingers and receive their support from a pair of U-shaped supporting means 492-a and 492-b through the assistance of shafts 494-a and 494-b journaled in said supporting means 492-a and 492-b. The supporting means 492-a and 492-b are fixedly disposed at the upper level 26. There are arms 496-a and 496-b which connect with the shafts 494-a and 494-b. Actuation of the arms 496-a and 496-b is by means of an air cylinder 498 through the intermediary of links 497-a, 497-b and a rocker arm 499. Retraction of these arms is by means of spring action. It will be observed that a tube 502 leads to an air valve 504 mounted at the intermediate level 24. By reason of a rocker arm 506 which is pivoted intermediate its end at 508 the air valve is moved to open

position. A cam 510 mounted on the cam shaft 88 engages the end of the rocker arm 506 lying remote from the air valve and provides the motivating force for said rocker arm.

Whereas the guide elements 490-a and 490-b assure extension of the flaps 244-a and 248-a into the thus formed carton it now becomes clear that a motivating force must be supplied in order to bend the side walls 242-a and 246-a, together with their attached flaps 244-a and 248-a. The mechanism for fulfilling this purpose is furnished in way of side bending plates 512-a and 512-b, these side bending plates being attached to a shaft 514-a and 514-b respectively. Each of the shafts is provided with an arm 516-a and 516-b by which the shaft may be properly rotated. Vertical links 518-a and 518-b have their upper ends pivotally connected to the arms 516-a and 516-b and their lower ends connected to opposite ends of a lever arm 520 pivotal about a central pivot point at 522. The pivot point 522 is supplied by means of a bracket 524 extending upwardly from the intermediate frame level 24. A vertically directed link 526 is pivotally connected to the lever arm 520 adjacent the locus of attachment of the vertical link 518-b and extends downwardly to an arm 528 pivotal about the shaft 414. The arm 528 extends under the cam shaft 422 and through the agency of a cam 529 on this shaft 422 the arm can be actuated at the proper interval so as to move the side bending plates 512-a and 512-b. Thus while the plates 512-a and 512-b are advanced through the medium of the cam 529 their return is effected by reason of a biasing spring which has connection between the intermediate level 24 and the vertical link 518-a. It will be understood that the flap bending plates 512-a and 512-b pivot during that period in which the tuck-in fingers 550-a and 550-b remain "tucked in."

While the foregoing description completes the cartoning procedure it will be seen that some provision must be made for the orderly removal of these cartons from the third and last work station. With this thought in mind it is to be noted that the spaced tracks 308 extend beyond the above referred to structure and that the upstanding lugs 398 at the forward end of the elevator frame 390 function to push each completed carton beyond that station where the cartoning procedure was completed. Consequently, the spaced tracks 308 are sufficiently long so as to lead to the vicinity of an upending plate 540 equipped with a vertical flange 542 for stopping the completed cartons as they are thrust thereon by the upstanding lugs 398 carried by the elevator frame 390 of the transport or advancing mechanism 380. By means of an upending arm 544 to which the upending plate 540 is attached the plate is caused to move from a horizontal to a substantially vertical position, a shaft 546 being directly connected to said arm 544 for moving the arm through the approximate 90 degree span. The shaft 546 has mounted thereon a sprocket 548 which has entrained thereabout a section of a chain 550. To one end of the chain 550 is attached a return spring 552, the return spring being connected at the lower level 22. At the other end of the relatively short length of chain 550 is attached a turnbuckle 554. The turnbuckle is in turn connected to one end of a lever arm 556 which lever arm freely encircles at its other end the shaft 414. By virtue of a cam 558 on the cam shaft 422 a medial portion of the lever arm 556 is engaged and is under the supervisory control of said cam.

Continuing with the description of the upending mechanism attention is called to the presence of a pair of laterally directed tracks 560. In super-adjacency with the beginning end of said tracks is an inverted U-shaped frame or super structure 562. A spring biased latch plate 564 is supported on the crossover portion of said inverted U-shaped frame 562, the function of said latch plate being to retain the filled or completed carton in an upstanding position after the plate 540 has moved them into said position.

At the far end of the tracks 560 is a switch 566

which deenergizes the solenoid 68 when the track is fully occupied with upended cartons of butter. An actuating slide 567 is instrumental in supplying the pressurized action needed to open the normally closed switch 566, said slide 567 being pushed by the upstanding filled carton against a bias provided by a weight 568 and a connected cord 569 suitably entrained over sheaves, one of which is shown at 571.

One of the features of the invention resides in the provision of load compensating means so that the entire apparatus can be operated with a minimum of power. By reason of the incorporation of such power or load compensating means into the apparatus the apparatus can be made especially sensitive to overloads that might come about through a faulty carton or some unforeseeable breakdown of parts. Accordingly, attention is now drawn to a first load compensating cam 570 mounted on one end of the cam shaft 88. Associated with this cam 570 is a lever arm 572 having an intermediate pivot point at 574; thus while one end of the lever arm is designed to ride against a specially contoured cam 570 the other end thereof is attached to one end of an energy storing spring 576, the other end of such spring being fixedly anchored to the upper level 26. A second load compensating cam 578 is mounted on the shaft 422. Associated with this particular cam is a bell crank 580 having its elbow portion freely encircling the cam shaft 414. The short arm of the bell crank which has been labeled 582 is engageable with the cam 578 whereas its longer arm 584 is attached to one end of a second energy storing spring 586. Consequently by selecting the proper profile or contour of the cams 570 and 578 it will be recognized that these cams can be rotatively adjusted and then fixedly pinned so as to exert a tensional pull on their respective springs 576 and 586 during periods of relatively low energy demand and that this energy is released when relatively large loads are encountered by the butter packaging apparatus.

To avoid any confusion it might be explained at this time that there is an auxiliary arm 588 fixedly connected to the shaft 414. This arm 588 has attached thereto an over center spring 590 which is anchored at its lower end to the frame level 22 and thereby helps in rotating the shaft 414 past a potentially troublesome point.

In order to obtain the best possible understanding of the apparatus and its functioning, reference should now be had to Figure 18 where there is presented what amounts to a schematic representation of the circuitry involved. The circuit depicted in this figure includes a pair of power lines 592 which are under the direct control of a manually actuatable line switch 594. There is furnished a start or run button 596 whose contacts are in circuit with a relay indicated generally by the reference numeral 598. The relay 598 has a coil 600 and a movable armature or core 602. Carried by the core 602 so as to be movable therewith is a plurality of normally open contacts 604, 606 and 608. In addition to the normally open contacts there is one set of normally closed contacts 610 which contacts are in series with a "power on" indicating light. The normally open contacts 604 function as "holding in" contacts, the normally open contacts 606 are merely in serial relationship with the drive motor 34, and the normally open contacts 608 are in circuit with the switch 566 which as previously indicated, is responsible for de-energizing the solenoid 68 when the upended filled cartons have accumulated to a desired number on the laterally extending tracks 560. Also in series with the run button contacts 596 and the coil 600 are overload contacts 614, these contacts being separated by reason of a bi-metallic element when the motor 34 draws too much power for its rated capacity. A set of stop contacts 616 serve to de-energize the relay 598 whenever the operator desires to do so. Other previously mentioned contacts are also in series with the relay coil 600. A jog switch labeled 618 includes a pair of normally open contacts 620 and a pair of normally closed contacts 622. It will be seen that

closure of the jog switch 616 will energize the relay 598 for only the period of time that the jog switch is manually depressed, since the normally closed contacts 622 are interlocked so as to open when the contacts 620 are closed; thus the holding in contacts 604 are ineffectual for maintaining the relay 598 in an energized state. While the circuitry presented in Figure 18 is not intended to be complete as to the various mechanical details constituting the butter packaging apparatus, nonetheless it will be perceived that certain of these mechanical parts do appear and will be of assistance it is believed in the orientation of the electrical circuitry with respect to the mechanical features of the invention.

Having in mind the construction and arrangement of the principal elements thereof, it is believed that a complete understanding of my invention may now be had from a description of the operation. Certain preliminary steps must of course be taken before the actual operation occurs; for instance, it is obvious that the magazine 114 must have included therein a suitable supply of carton blanks 116 and as already indicated we will deal expressly with the type of carton blank labeled 116-a which appears in detail in Figure 8. Further, it will be assumed that the line switch 594 has been closed and that the compressor motor 28 has thereby been placed in operation. Also it will be presumed that the push button switch 596 has been closed so that the relay 598 is energized so that the drive motor 34 is in operation. Immediately upon the activation and operation of the motor 34 the conveyor 46 begins to move and its movement feeds a random supply of quarter pound prints of butter 49 onto the platform 104.

Prior to describing what takes place upon the arrival or deposit of printed butter onto the platform 104 it will be further assumed that a carton blank 116-a has been fed downwardly by the feeding mechanism 110. Thus while the operation is of a continuous nature the foregoing assumptions have of necessity been made in order to provide an arbitrary starting place for the actual operation itself.

In view of the preliminaries dealt with above, attention is now drawn to both Figures 5 and 19. Figure 5 does not show a blank in position but it may be explained that all of the operating parts of the feeding mechanism 110 are illustrated in the various positions that they assume when a carton blank is resting on L-shaped feet 234 which position the blanks at the appropriate elevation for the first bending operation. This disposition of the blank 116-a is clearly depicted in Figure 19 and from this figure it will be perceived that the front wall section 234-a resides at the same elevation as are the rectangular wings 270. Actually the blank 116-a has been placed prior to the inward actuation of said wings 270 and therefore Figure 19 presents a situation that is representative of a slightly more advanced stage than that which we have assumed to have transpired in order to initiate an appropriate description of the operational sequence.

Under these assumed conditions the switch 108 on the platform 104 has not as yet been closed by reason of four quarter pound prints of butter 49 having been deposited on said platform. Once the four quarter pound prints of butter are received on the platform 104 however then the switch 108 is closed and this results in the immediate energization of the solenoid 68. It is the energization of the solenoid that results in the retraction of the pivotal latch arm 62 together with its catch 64 so that there is no longer provided any obstructive interference with the pawl 54. Consequently the pawl 54 becomes engaged with the ratchet 52 resulting in the rotation of the horizontal shaft 90. By way of review it will be remembered that all of the parts with the exception of the conveyor 46 are driven from the shaft 80.

It of course follows from the above happening that the cam shaft 88 is immediately placed into rotation

and causes its cam 280 to block the rocker arm 276 in a direction to open the air valve 274. This air valve immediately furnishes air under pressure from the compressed air tank 32 to the air cylinders 272. Inasmuch as the rectangular wings 270 are operated by said air cylinders 272 both of the wings are moved inwardly into confronting relation with the section 234-a of the blank 116-a. Thus what has transpired up to this time results in what has been pictured in the fragmentary perspective view set forth in Figure 19.

Two things have now begun to happen substantially concurrently with each other: first, the pusher frame 100 under the forced influence of the cam 96 begins to transfer the four prints of butter that have actuated the switch 108 transversely to the first work station; secondly, the horns 282-a and 282-b begin their bending stroke at this station. With respect to the operation of the horns 282-a and 282-b attention should be shifted from Figure 5 which pictures the initial or inactive position of these horns to Figure 10 where the horns are shown in an intermediate solid position. A facile transition between Figure 5 and Figure 10 is easily made by showing the position of the horns 282-a and 282-b in phantom outline, this phantom outline corresponding to the solid line position of the horns in Figure 5. Although the horns 282-a and 282-b are not pictured in Figure 20, nonetheless the carton blank 116-a as it appears in Figure 20 corresponds substantially to the view thereof depicted in Figure 10. The point to be stressed at this particular time is that the bending of the carton blank is taking place about the upper and lower edges of the rectangular wings 270. During this bending operation the printed butter is in the process of being transferred from the platform 104 to the platform 306. Because of the utilization of the wings 270 and the accomplishment of this initial bending action, it becomes manifest that the presence of the butter on the platform 306 is not needed and actually one of the features of the invention resides in not having the butter advanced to the platform 306 in order to effect this first bending operation. This permits a faster overall operation of the machine and it should be fully understood that the use of the wings 270 does not subject the butter to any compressive or distortive forces; therefore not only is the action of the butter packaging apparatus speeded up but the initial shape of the printed butter is preserved even though such butter might be in a soft or semi-fluid condition. By so doing, the need for keeping the butter in a frigid state is obviated. This greatly simplifies the task of handling the butter in the creamery in which it is being packaged.

While the butter continues to be advanced laterally by the pusher frame 100 during the operation of the horns 282-a and 282-b completion of the transfer operation is not made until after the horns have moved to the end of their arcuate stroke. This condition is presented in Figure 21.

After the above bending operation has been consummated the butter together with its partially enwrapped carton blank 116-a is ready for longitudinal advancement to the next station.

It is the primary responsibility of the longitudinally reciprocal pusher frame 298 to advance the butter and its now U-shaped carton blank 116-a to the next or second work station. Concomitantly with the forward movement of the frame 298 the frame 100 begins to retract, it having performed its duty at this point. However, it perhaps should be explained that the switch 108 is maintained in a closed position during the advancement and retraction of the frame 100 by reason of one side thereof engaging this switch 108. Also synchronized with the forward movement of the pusher frame 298 is the retraction of the curved horns 282-a and 282-b. This synchronized retraction is of significance inasmuch as these horns are in engagement with the

upper and lower surfaces of the carton blank and actually assist in the advancement of the carton blank and its butter contents to the next station. Consequently the pusher frame 298 which is pressing against the butter does not have to supply all of the moving force. This is a nicety of the invention inasmuch as it relieves the butter when in a rather soft condition from any more compressive and hence distortive forces than are necessary to effect the desired advancement.

Figure 11 illustrates the pusher frame 298 at the end of its advancing stroke and hence pictures the butter at the second work station which will now be discussed in detail. Once having reached the position shown in Figure 11 there is no reason for the pusher frame 298 to remain in its extended position and it immediately begins to retract but of course leaving the butter at this particular station. The first thing that occurs at this particular station is the bending of the flaps 244-a and 248-a into parallel vertical planes. It is the movable forming members 322-a and 322-b that accomplish this operation in conjunction with the fixed forming plates 320-a and 320-b. Consequently in order to assure that this operation takes place right after the arrival of the butter (and the carton blank which has been partially folded thereabout) at this station, the cam 332 on the cam shaft 88 is contoured so as to rock the rocker arm 330 in a direction to open the air valve 328. Opening of the air valve admits air to the two air cylinders 324-a and 324-b, thereby resulting in the forced moving of the forming members 322-a and 322-b. Actually, the foregoing forming operation takes place substantially at the same time as does another operation, and, therefore, while Figure 23 in theory represents a subsequent step to that shown in Figure 22, the two figures are in reality indicative of what occurs in substantial correspondence.

At any rate in discussing Figure 22 it will be assumed that the pusher frame 298 has been retracted sufficiently so that there will be no interference with the upward movement of the lower pivotal fingers 340. The proper orientation of the cam 354 on its cam shaft 206 assures this inasmuch as the cam shaft 206 is rotating in synchronism with the cam shaft 88. Because of the cam action afforded by the cam 354 the pivotal fingers 340 are pivoted upwardly so as to engage the rear wall section 252-a, thereby flexing said rear wall section into confronting relationship with the rearmost quarter pound of butter.

The angle through which the pivotal fingers 340 move in bending the rear wall section 252-a into the position just described is clearly shown in Figure 12 where the original or inactive position of the fingers 340 is depicted in solid outline, whereas the final position of these fingers is shown in phantom outline. Attention is also drawn to Figure 22 where the fingers 340 are shown in their fully advanced position.

It is of course the function of the upper pivotal fingers 358 to bend the other rear wall section 350-a downwardly and this action is precipitated immediately upon the fingers 340 having completed their bending operation. Accordingly, under the influence of the cam 372 which is on the cam shaft 206 the upper fingers 358 start to move downwardly as the lower fingers 340 are withdrawn. By reason of the previously mentioned dwell period formed on the cam 372 a pause is introduced in the forward movement of the fingers 358. This pause occurs just before the section 250-a would have encountered the withdrawing fingers 340. The pause is not of very long duration, it being only long enough to permit the uninterfered retraction of said fingers 340 without the wall section 252-a having a chance to flex out of position due to any resiliency that may remain. At the conclusion of this short dwell interval the fingers 358, still under the influence of the cam 372, proceed to complete their bending operation. The completion

of this bending operation is shown in Figure 12 where it will be discerned that the fingers 358 have brought the section 250-a into a contiguous relationship with the previously bent wall section 252-a.

Next to occur is that the cam 408 on the cam shaft 88 rotates into a position so as to actuate the rocker arm 404 in a direction to open the air valve 402. Opening of the valve 402 is responsible for furnishing air under pressure to the air cylinder 399. Air thus supplied to the air cylinder raises the elevator frame 390 together with its upstanding lugs 398. In Figures 5 and 10 the lugs on the frame 390 are shown in dotted outline, these lugs in these two figures at this moment being in a lower position. However, Figure 12 depicts the lugs, together with their integral frame 390, in a raised position which has been accomplished by virtue of having supplied the air cylinder 399 with compressed air from the tank 32. It may be explained at this time that the rearmost upstanding lugs 398 are in staggered relationship with the pivotal fingers 358; consequently the moving upwardly of the lugs 398 is free to occur even though the fingers 358 at this moment have not as yet been retracted.

With the elevator frame in its raised position, as described in the preceding paragraph, the transport or advancing mechanism 380 is now ready to be advanced to the third work station. The cam 420 on the cam shaft 422 is properly oriented so that it acts against the bell crank 412 which in turn moves the draw bar link 410, the draw bar link being connected directly to the carriage 382 of the drag mechanism 380. Consequently the drag mechanism proceeds to move forwardly and by reason of the rear upstanding lugs 398 it will be seen that the thus far cartoned butter is carried along therewith.

In Figure 12 it will be noted that the rollers 430 on the carriage 382 on the transport or drag mechanism 380 are in engagement with the fragmentarily depicted deflector arms 432. As the mechanism 380 advances, though, the rollers 330 constantly permit the deflector arm 432 to pivot in a clockwise direction as viewed in Figure 12 and Figure 14, the pivotal movement being effected through the instrumentality of the spring 440. This action results in the transfer of arms 436, which are movable in unison with said deflector arm 432, to move in a clockwise direction together with their pickup plates 438. It is the office of the pickup plates 438 to make certain that the vertically directed flaps 244-a and 248-a remain in substantially parallel planes during the transfer of the carton to the next station. Ultimately the rollers 430 leave the deflector arms 432 but the apparatus is designed so that by this time the transfer operation has been substantially completed.

While Figure 14 is intended primarily to show the butter in the process of being advanced, it will be observed that this particular figure also shows substantially the same mechanism depicted in Figure 15. It is Figure 15 that best designates the particular station with which we will now deal, although said Figure 15 is illustrative of a more advanced stage of the cartoning procedure than is Figure 14. In brief, Figures 14 and 15 provide a good transitional picturization of what transpires at this third work station. It might be explained at this point that the upper pivotal fingers 358 that were utilized in bending the rear wall section 350-a downwardly are retracted as the advancing mechanism 380 moves forwardly; thus the retraction of the pivotal fingers 358 is such that they will be in readiness for the next carton blank that comes along.

The first thing that occurs after the arrival of the butter and the carton blank at this particular station is that the tuck-in fingers 350-a and 350-b are operated so as to bend in the various tabs 336-a, 354-a and 356-a. Thus the fingers 350 are moved from the position in which they appear in Figure 14 to the position they appear in Figure 15. This position is also highlighted in the per-

spective view of Figure 24. From Figure 24 it will be observed that there is a slight amount of what might be termed "overtravel" imparted to the movement of the fingers 450 which results in an upward bowing of the top wall panel 238-a and a downward bowing of the bottom 240-a. The timing of these tuck-in fingers 450 is provided by the cam 482 which is properly oriented on the cam shaft 422 so that the operation of said tuck-in fingers occurs only after the arrival of the advancing mechanism 380 to the particular station with which we are now dealing.

Incidentally, the transport or advancing mechanism 380 has now completely served its purpose and at this time the cam 498 which has opened the air valve 402 rotates into a position so that the air valve is free to close. With its supply of air shut off, the air cylinder 399 promptly lowers its elevator frame 390 together with the upstanding lugs 398 carried on this frame 390. Concurrently with the lowering of the elevator frame 390 (by reason of the cutting off of the air supply to the air cylinder 399) is the opening of the air valve 504 by means of the cam 510. This furnishes air to the air cylinder 498 which is responsible for actuating the curved radius flap lead or guide elements 490-a and 490-b. The respective positions into which these guide elements 490-a and 490-b are urged are best viewed in Figures 16 and 25.

With the guide elements 490-a and 490-b in position the next action that transpires is that the side bending plates 512-a and 512-b are pivotally moved so as to act against the side wall section 242-a and 246-a. These particular plates are moved by means of the cam 529. During the pivotal movement of the side bending plates 512-a and 512-b it will be seen and appreciated that the curved guide elements 490-a and 490-b constrain the flaps 244-a and 248-a so that they are guided with ease into the still bowed upper and lower walls 238-a and 240-a respectively of the now almost completed carton formed from the blank 116-a. Close inspection of Figure 16 will reveal the side bending plates 512-a, 512-b in their normal or inactive position whereas Figure 25 shows these plates in an almost fully pivoted relationship; thus Figure 25 pictures the flaps 244-a and 248-a almost completely inserted between the bottom wall 240-a and the top wall 238-a and the bottom and top of the printed butter.

Figure 26 corresponds to Figure 25 but illustrates the bending of the blank 116-b. Accordingly, the re-oriented members have had their reference numerals primed, being denoted as 490-b' and 512-b'.

After this particular stage of completion has been achieved, then the tuck-in fingers 450-a and 450-b begin to retract inasmuch as they have now served their full purpose. Simultaneously with the retraction of the tuck-in fingers 450-a and 450-b is the moving back of the transport or advancing mechanism 380. It has already been stated that elevator frame 390 has been lowered, so of course there is no interference between the forward lugs 398 as the mechanism 380 returns to its "home" position. With the tuck-in fingers 450-a and 450-b retracted and thus out of the way, the side bending plates 512-a and 512-b are then further actuated by their cam 529 into a substantially vertical position, which position completes the closing of the side walls 242-a and 246-a. Stated somewhat differently, the flaps 244-a and 248-a are now in a fully inserted condition and the sides 242-a and 246-a are in parallel vertical planes. The completed carton with the thus encased four prints of butter is presented in Figure 27.

Of rather minor importance is the fact that the side pending plates 512-a and 512-b are returned to their retracted position during the latter portion of the return travel of the transport or drag mechanism 380 to its "home" position. A more important point to be stressed at this time, however, is that the completely cartoned

5

15
20
25

butter remains at this last station until the transport mechanism 380 brings forward a succeeding partially cartoned package of butter. It is when the mechanism 380 again reaches this last station that the forward lugs 398 push the completed carton of butter to the end of the spaced tracks 308. The particular carton that we have been describing still does not reach the upending plate 540, although it shoves the preceding carton ahead of it onto said plate. The particular carton which we have been talking about must await the arrival of a still different partially completed carton at this last station. Once the completed carton has been shoved onto the upending plate 540 the cam 558 is responsible for moving the plate 540 from its horizontal position to a substantially vertical position which causes the fully cartoned butter to be upended at the completion of the upending travel of the plate 540. The carton is engaged by the latch plate 564 so that there is no opportunity for it to topple over against the plate 540 as it returns to its horizontal position. Succeeding fully cartoned pounds of butter merely shove the carton that we have been describing forward along the laterally directed tracks 560. Should an attendant not be in the immediate vicinity when the tracks 560 become fully loaded with cartoned butter, then continuing feed of such fully completed cartons will merely shove the foremost cartons against the switch 566 and this switch will de-energize the solenoid 68 to halt the cartoning process. Thus it will be perceived that the apparatus described herein is fully automatic in its operation and does not require the constant presence of an attendant.

For the purpose of simplifying the operational sequence as much as possible the functioning of the carton blank feeder 110 was postponed, it will be recalled. Thus the operation was started with a blank in position for its first bending operation. Although it is believed readily apparent from the earlier presented description of the carton blank feeder 110, nonetheless a brief account of its operation will probably be helpful to a full and complete understanding of the apparatus. In order to orient the functioning of the feeder 110 with what is taking place at a given moment as far as the operation of the rest of the equipment is concerned, attention is directed to Figure 5. In this position the lower fingers 340 which function to bend the rear wall section 252-a are just beginning to return to their retracted position and the upper fingers 358 are in the process of moving forwardly in order to bend the upper wall section 250-a downwardly.

As shown in Figures 5 and 6, the suction cups 142 are in a raised position and have been urged into engagement with the foremost blank 116. Also by reason of the particular position assumed by the cam 186 the vacuum valve 184 has been opened so as to connect the suction cups 142 to the intake of the compressor 30. Thus a vacuum has been applied to the suction cups 142 and they are about to be moved in a counter clockwise direction as viewed in Figure 5. Close inspection of the dotted outline of the cam 156 as it appears in Figure 5 will show that this cam is in a rotative position in which the L-shaped rocker arm 154 is in its most clockwise pivotal position, it being pivotal about the pivot point 152. However, as the cam 156 rotates in a counter clockwise direction, it will cause the rocker arm 154 to move in a counter clockwise direction about the pivot point 152 to thereby move the suction cups 142 away from the stack of blanks 116. In this way the foremost blank 116 is literally peeled away from its stack, its lower edge riding over the dogs 120. During this particular portion of the operation the blank being removed is pivoted at its upper edge with respect to the bracket 138.

Once having peeled off the foremost blank 116 the rocker arm 154 continues to be pivoted in a counter clockwise direction until the lower end thereof riding

against the cam 156 reaches a high portion of said cam which results in a stopping of further pivotal movement for the prescribed interval. At this time the bar 160 is urged downwardly via its follower 170 which is riding against the cam 172. Consequently the upward biasing action of the spring 174 is readily overcome and by virtue of the slotted bearing 176 on said bar 160 the suction cups now begin their downward travel with the carton blank 116 gripped thereby. Just as the suction cups 142 reach the bottom of their vertical travel the cam 156 permits the vacuum valve 184 to close so that vacuum is no longer applied to the suction cups. Concurrently with this happening is the riding of the lower end of the rocker arm 154 onto the highermost arcuate surface of the cam 156 which causes the telescoping arms 145 on which are mounted the suction cups 142 to move slightly farther away from the carton blanks. In this way any tendency for the carton blank to remain gripped by the suction cups 142 is precluded inasmuch as the further movement of the telescoping arms 145 is relative to the ejector foot 178 supported on the slotted bearing 176. Because of this action the ejector foot 178 makes certain that the blank 116 is dislodged from the suction cups 142 so that it drops into engagement with the gripping teeth 182 on the mutilated feed rollers 180. From this point on, the feed rollers 180 are responsible for lowering the blank downwardly and do so until the bottom edge of the blank reaches the L-shaped feet 234 which position the blank for its first bending operation as heretofore described in detail. It might be explained that the horns 282-a and 282-b are in the process of performing their bending operation on the preceding blank and it is during the retraction of the horns 282-a and 282-b that the downward feeding or lowering of the blank 116 occurs through the agency of said feed rollers 180.

One of the features of the invention is that the apparatus herein described is capable of performing more than one cartoning operation at a single time. By way of quick explanation it can be pointed out that while the horns 282-a and 282-b are performing their bending operation the transport or advancing mechanism 380 is advancing a preceding partially completed carton. With this information, it is felt that the reader will be able to orient in his own mind the various operations that are all being performed concurrently with each other inasmuch as a complete operational sequence has already been detailed.

It can easily be appreciated that certain portions of the operation will require considerably more power than during other portions. Reference has already been made to the load compensating cams 570 and 578. Without going into detail as to precisely what periods of the operation the heavier load requirements it will be said by way of review at this time that these load compensating cams 570 and 578 are so oriented in order that their respective energy storing springs 578 and 586 will have adequate energy stored therein for release during the periods when the load demands have increased. In this way the gear sections 72 and 74 of the overload clutch can be set through the agency of their strings 73 so that they can be expected to separate under a less load than the peak load would require. Also the overload switch 14 can be set so that the motor 34 will be de-energized on lesser electrical overload than if the compensating cams were not utilized.

As many changes could be made in the above construction and many apparently widely different embodiments of the invention could be made without departing from the scope thereof, it is intended that all matter contained in the above description and as shown in the accompanying drawings shall be interpreted as illustrative and not in a limiting sense.

It is also to be understood that the language used in the following claims is intended to cover all the generic and specific features of the invention herein described

and all statements of the scope of the invention which, as a matter of language, might be said to fall therebetween.

What is claimed is:

1. In a butter packaging machine, means for positioning a carton blank in a substantially vertical plane, means movable into an adjacent relation with a portion of one face of said carton blank, said second-mentioned means having upper and lower edges about which said carton blank is to be bent, means engageable with the opposite face of said carton blank for bearing against said carton blank at elevations above and below said upper and lower edges of said second-mentioned means to effect a bending operation about said edges, and transfer means for positioning the printed butter in close proximate relationship to the engageable means and between the positions assumed by the bent portions of the carton when the carton is bent by said second mentioned means and the engageable means.
2. In a butter packaging machine, means for positioning a carton blank in a substantially vertical plane, means movable into an adjacent relation with a portion of one face of said carton blank, said second-mentioned means having upper and lower edges about which said carton blank is to be bent, means engageable with the opposite face of said carton blank for bearing against said carton blank at elevations above and below said upper and lower edges of said second-mentioned means to effect a bending operation about said edges, and means for transferring printed butter substantially parallel to said one face from a laterally displaced position into a proximal relationship with said carton blank portion.
3. A butter packaging apparatus in accordance with claim 2 including means for simultaneously actuating said bending means and said transfer means after said second-mentioned means has been moved into juxtaposition with said carton blank portion.
4. In a butter packaging machine, means for positioning a carton blank in a substantially vertical plane, a pair of wing members movable into a confronting relation with a portion of one face of said carton blank, said wing members having upper and lower parallel edges, and means for bending said carton blank about said upper and lower edges to form a wall of the carton.
5. A butter packaging machine in accordance with claim 4 in which said last-mentioned means includes an upper and lower bending member normally disposed adjacent the other face of said carton blank, and means for moving said upper and lower members against said carton blank at an elevation above and below the edges of said wing members to effect the bending of said carton blank.
6. A butter packaging machine in accordance with claim 5 including upper and lower shafts disposed in a parallel relation with said carton blank, said bending members constituting curved horns pivotally carried by said shafts.
7. A butter packaging machine in accordance with claim 6 including first transfer means for moving printed butter from one side into the U-shaped blank formed by said curved horns as said horns are performing their bending operation, and second transfer means for engaging the side of the butter farthest from said carton wall after said first transfer means has completed its transfer operation to move said carton blank and its partially cartoned butter in a forward horizontal direction normal to said vertical plane.
8. A butter packaging machine in accordance with claim 7 in which the retraction of said horns is synchronized with the forward movement of said second transfer means, whereby the pressure exerted on the butter by said second transfer means is lessened.
9. In a butter packaging machine, means for positioning a carton blank in a given plane, engageable means engageable with one side of said carton about which said carton blank is to be bent to form one wall of the

carton, blank bending means for engaging the other side of said carton to effect the bending of said carton blank about one side of said engageable means, means for feeding printed butter into juxtaposition with said engageable means while said bending means is bending said carton blank about one side of said engageable means, and actuating means for advancing and retracting said engageable means to and from its blank engaging position.

10. A butter packaging machine in accordance with claim 9 in which said actuating means retracts said engageable means after completion of the butter feeding operation by said feeding means to a non-interfering position, and reciprocal means for advancing said butter in the retractive direction of said engageable means.

11. In a butter packaging machine, a magazine superstructure for holding a stack of carton blanks, suction cup means for dislodging the foremost blank from said stack and lowering said foremost blank to a preferred elevation, mutilated feed roller means for engaging said foremost blank at said preferred elevation to lower said blank still further, means for engaging the lower edge of said blank to retain said blank at its lower-most position, means for bending said blank into a substantially U-shaped configuration while in its lower-most position to form one wall of the carton, actuating means for said suction cup means and said roller means, sensing means for inactivating said actuating means when the stack of carton blanks becomes deflected, and means associated with said sensing means for rendering said sensing means ineffectual in its inactivating function during the normal spacing interval between the upper edge of a preceding blank and a lower edge of a successive blank.

12. A butter packaging machine in accordance with claim 11 in which said actuating means includes a cam shaft and an electric motor for driving same and in which said sensing means includes a feeler element and a switch that is closed when said feeler element is in engagement with a blank in the process of being fed, said switch being in series with said motor, and said associated means including a cam on said cam shaft and a switch in parallel with said first-mentioned switch, said last-mentioned switch being closed by said cam during said interval between carton blanks.

13. In a butter packaging machine, a superimposed magazine for holding a stack of substantially vertically arranged carton blanks, said magazine including a downwardly sloping track upon which the lower edges of said blanks rest while in said magazine, an upstanding dog element at the forward end of said track for engaging the lower edge of the foremost blank contained in said stack and means for releasably engaging the upper edge of said foremost blank, a rock bar, a downwardly projecting telescoping arm having its upper section attached to said rock bar, a suction cup supported by the lower section of said arm, a cam shaft, a first cam on said cam shaft for rocking said rock bar to swing said suction cup away from said stack of blanks, vacuum means including a valve connected to said suction cup, a second cam on said cam shaft for opening said valve to apply vacuum to said suction cup during its swing away from said stack so that the foremost blank is carried therewith, a lift bar constrained for substantially vertical movement, said lift bar having a horizontally directed slotted bearing engageable with a transverse element connected to the lower section of said telescoping arm so as to permit the swinging of said arm and its supported suction cup, a third cam on said cam shaft for lowering said lift bar after completion of said swinging movement, said second cam being contoured so as to close said valve when said lift bar has reached the lower end of its stroke, feed roller means driven in unison with said cam shaft for lowering said foremost blank after its release from said suction cup, a bottom support for retaining said blank at a preferred fixed elevation, and bending means for

bending said blank into a substantially U-shaped configuration while at its fixed elevation to form one wall of the carton.

14. A butter packaging machine in accordance with claim 13 including an ejector element carried by said slotted bearing, said first cam being contoured so that said rock bar is rocked farther when said lift bar reaches the lower end of its stroke in a direction to swing said suction cup to a position past said ejector element, whereby said ejector element forcibly urges said blank from said suction cup.

15. In a butter packaging machine, means for feeding a carton blank downwardly to a preferred elevation, said carton blank then residing in a vertical plane, means for bending said blank into a U-shaped configuration at said preferred elevation to form a forward carton wall, means for feeding a plurality of butter sections laterally into the confines of said U-shaped carton blank, means for engaging the rearmost butter section so as to advance said butter and its carton blank to a succeeding work station, lower pivotal means disposed at said succeeding station for bending a lower rear wall section of the blank upwardly, and upper pivotal means for bending an upper rear wall section downwardly, both of said last two means cooperating to form the rear wall of the carton.

16. A butter packaging machine in accordance with claim 15 in which said last two means include respective groups of staggered fingers.

17. In a butter packaging machine, means for feeding a carton blank into a preferred vertical position at one station, means for bending said blank into a substantially U-shaped configuration at said one station to form the forward wall of the completed carton, means for introducing printed butter into said U-shaped carton blank at said one station, means for advancing said carton blank and its butter to a second station, means for bending lower and upper rear wall sections of said blank into vertical juxtaposition with the rear side of said butter to form the rear carton wall while the partially cartoned butter is at said second station, and forming means for bending side sections of the blank into parallel vertical planes to thereby form flaps at said second station.

18. A butter packaging machine in accordance with claim 17 in which said flap forming means includes a vertically disposed plate member spaced somewhat from either side of the butter and a vertically movable forming plate cooperable with each of said fixed plates for effecting the bending of said flaps.

19. A butter packaging machine in accordance with claim 17 including a transport mechanism for advancing said butter to a third station, said mechanism having a subjacent carriage constrained for longitudinal travel between said second and third stations and an elevatable frame having upstanding lugs engageable with the rear carton wall when in a raised position.

20. A butter packaging machine in accordance with claim 19 in which said transport mechanism includes an air cylinder for raising said frame after the bending operations at said second station have taken place.

21. A butter packaging machine in accordance with claim 19 including means actuatable by said transport mechanism for maintaining the vertical disposition of said flaps during advancement of the partially cartoned butter from said second work station to the third work station.

22. A butter packaging machine in accordance with claim 17 including means at said third work station for bending said side sections including said flaps in a direction so as to insert said flaps between said butter and adjacent portions of the carton blank.

23. A butter packaging machine in accordance with claim 22 in which said bending means includes a pair of pivotally mounted plates, the packaging machine further including curved guide means for assuring the proper insertion of said flaps.

24. In a butter packaging machine, means for bending a carton blank relative to printed butter to form the front, top, bottom and rear walls of the carton when completed, said bending means leaving lateral tabs projecting from said front and rear walls, a side wall section extending in one lateral direction from said top wall, a side wall section extending in an opposite lateral direction from said bottom wall and vertical flap portions integral with said side wall sections, a pair of pivotal fingers at each side of the partially completed carton mounted for pivoting about upper and lower transverse axes for bending said tabs into adjacency with the sides of the butter, and a pivotal plate at either side of the partially completed carton for engaging said sections from horizontal planes into vertical planes along side said butter but outwardly of said tabs.

25. A butter packaging machine in accordance with claim 24 including means associated with said pivotal plates for assuring insertion of said flap portions between the upper butter surface and the top wall in one instance and the lower butter surface and the bottom wall in the other instance.

26. A butter packaging machine in accordance with claim 25 including means on said tab bending fingers for engaging the partially completed carton in both of said instances to bow the top wall upwardly away from the upper butter surface and bow the bottom wall downwardly away from the lower butter surface to facilitate insertion of said flap portions.

27. In a butter packaging machine, means for feeding a succession of pre-scored carton blanks into a vertical plane at a first work station, means for bending each carton blank into a substantially U-shaped configuration to form a top, bottom and front wall, means for laterally moving a predetermined number of prints of butter into the confines of each U-shaped carton blank as it is being bent, means for longitudinally engaging the rearmost print of butter to advance said butter and its carton blank to a second work station, respective means situated at said second work station for bending upwardly and bending downwardly carton sections to form a rear wall, further means at said second work station for bending side sections into parallel vertical planes to form flap portions, track means extending from said second work station to a third work station, a transport mechanism underlying said track means and movable axially therealong including an elevatable frame provided with upstanding means engageable with said rear carton wall to move the partially cartoned butter from said second work station along said track means to said third work station, means actuatable by said transport mechanism for maintaining said flap portions vertical as said partially cartoned butter is advanced to said third station, tab bending means situated at said third work station for bending laterally projecting tabs integral with said front and rear walls into planes substantially parallel to the sides of the printed butter, and means for bending side sections lying innerjacent said flap portions in a manner to cause said flap portions to become inserted between said printed butter and a section of the carton.

28. A butter packaging machine in accordance with claim 27 including curved fingers movable into position to guide and thus assist in the bending of said last-mentioned side sections so that said flap portions will be properly inserted.

29. A butter packaging machine in accordance with claim 28 in which said elevatable frame is provided with additional upstanding means spaced forwardly of said first-mentioned upstanding means so as to engage and move a preceding carton of butter from said third work station to a point therebeyond.

30. A butter packaging machine in accordance with claim 29 including upending means for tilting the cartoned butter received from said third work station from a hori-

zontal position to a vertical one, said track means extending from said third work station to said upending means.

31. A butter packaging machine in accordance with claim 27 in which one of said last-mentioned side sections is integral with the bottom wall of the carton and the other side section is integral with the top wall, and said last-mentioned means includes one pivotal plate for bending said one side section upwardly to insert its adjacent flap portion between the upper surface of the butter and the top carton wall and includes a second pivotal plate for bending said other side section downwardly to insert its adjacent flap portion between the lower surface of the butter and the bottom carton wall.

32. A butter packaging machine in accordance with claim 27 in which both of said last-mentioned side sections are integral with the bottom wall of the carton, and said last-mentioned means includes a pair of pivotal plates for bending said last-mentioned side sections upwardly to insert said flap portions between the upper surface of the butter and the top wall.

33. In a butter packaging machine, a frame having lower, intermediate and upper levels, power means located at said lower level, a plurality of cam shafts at said intermediate level, drive means extending between said power means and said cam shafts, first carton bending means at said upper level for forming a top, bottom and front wall, second carton bending means at said upper level spaced from said first bending means for bending sections of the carton blank to form a rear wall, third carton bending means at said upper level for bending additional carton sections to form side walls, and a cam for each of said first, second and third bending means on said cam shafts for actuating said respective bending means.

34. A butter packaging machine in accordance with claim 33 including a carton blank feeding mechanism comprising a magazine for holding a stack of carton blanks, feed rollers for lowering a carton blank to said first bending means and suction cup means for removing the foremost carton blank from said stack and transferring same to said feed rollers, a vacuum valve connected to said suction cup means, a cam associated with said feed rollers for opening said vacuum valve, compressor means at said lower level, and means connecting the intake of said compressor means to said vacuum valve so that vacuum will be applied to said suction cup means during the transfer of said foremost carton blank from said stack to said feed rollers, said cam being contoured so as to open said vacuum valve during said transfer.

35. A butter packaging machine in accordance with claim 33 in which said first bending means includes a pair of laterally movable wing members movable into cooperable relationship with a portion of a carton blank, a pair of air cylinders for actuating said wing members into said cooperable relationship, an air valve connected to said air cylinders, a cam carried by one of said cam shafts for opening said air valve, compressor means at said lower level, and means connecting the discharge of said compressor means to said air valve so that air under pressure will be supplied to said air cylinders during the first bending operation, said cam being contoured so as to open said air valve during the first bending operation.

36. A butter packaging machine in accordance with claim 33 including means for supplying printed butter to said first bending means, reciprocable pusher means for advancing the partially cartoned butter from said first bending means to said second bending means, a cam on one of said cam shafts for actuating said pusher means, a transport mechanism for advancing the partially cartoned butter from said second bending means to said third bending means, and an additional cam on one of said cam shafts for actuating said transport mechanism.

37. A butter packaging machine in accordance with

claim 36 in which said transport mechanism includes an elevatable frame for engaging the partially cartoned butter when said frame is raised and an air cylinder for raising said elevatable frame, the packaging machine also including an air valve connected to said air cylinder, a cam carried by one of said cam shafts for opening said air valve, compressor means at said lower level, and means connecting the discharge of said compressor means to said air valve so that air under pressure will be supplied to said air cylinder during the advancement of said transport mechanism.

38. In a butter packaging machine, respective carton bending means disposed at first, second and third spaced work stations, first transfer means for advancing printed butter to said first work station, second transfer means for advancing the partially cartoned butter from the first work station to the second work station, third transfer means for advancing the still more fully cartoned butter from the second work station to the third work station, respective cam means for actuating the several bending means and the several transfer means, motor means for driving said respective cam means, additional cam means mechanically coupled to said respective cam means, follower means engaged with said additional cam means, and spring means connected to said follower means, said additional cam means being contoured so that mechanical energy is stored in said spring means during intervals of relatively low power demands and released to said respective cam means during intervals of relatively great power demands.

39. In a butter packaging machine, a conveyor for moving a plurality of printed butter sections therealong, a stationary horizontal platform for receiving the butter sections discharged from said conveyor, switch means disposed adjacent that edge at said platform remote from the conveyor, the foremost butter section being advanced across said platform into actuating engagement with said switch means by successive butter sections being fed onto said platform by said conveyor, means laterally displaced from said switch means for positioning a pre-scored carton blank in a vertical plane, a pair of wing members provided with upper and lower edges movable into confronting adjacency with a portion of one side of said carton blank which is to form one wall of the completed carton, said wing members and said carton blank

portion having heights corresponding to that of the butter sections, a pair of curved horns pivotally mounted on the other side of said carton blank at elevations above and below said carton blank portion, means for moving said horns into engagement with said carton blank to effect bending thereof about the upper and lower edges of said wing members, first transfer means including a laterally movable head member having a width substantially equal to the combined width of a predetermined member of butter sections, the head member being movable upon actuation of said switch means to shift said predetermined number of butter sections transversely into alignment with said carton blank portion during the bending of said carton blank by said curved horns, means for retracting said wing members after the carton blank has been bent by said horns, and second transfer means including a longitudinally movable head member for engaging the rearmost butter section to move the partially cartoned butter to a subsequent work station.

40. In a butter packaging machine, a magazine superstructure for holding the stack of carton blanks, suction cup means for dislodging the foremost blanks from said stack and lowering said foremost blanks to a preferred elevation, mutilated feed roller means for engaging said foremost blank at said preferred elevation to lower said blank still further, means for engaging the lower edge of said blank to retain said blank at its lowermost position, and means for bending said blank into a substantially U-shaped configuration while in its lower-most position to form one wall of the carton, said means for bending said blank including a pair of laterally movable rectangular wing members confrontable with one face of the carton and curved horns forcibly engageable with the other face of the carton above and below the portion thereof that is to form said wall so as to effect the bending of said blank into its U-shaped configuration.

UNITED STATES PATENT OFFICE
CERTIFICATION OF CORRECTION

Patent No. 2,945,334

July 19, 1960

Arthur Perrault

It is hereby certified that error appears in the above numbered patent requiring correction and that the said Letters Patent should read as corrected below.

Column 5, line 25, for "a" read -- as --; column 11, lines 22 and 23, for "numerial" read -- numeral --; column 13, line 16, for "uuper" read -- upper --; column 17, line 58, for "350-a" read -- 250-a --; lines 69 and 70, for "peremit" read -- permit --; column 18, line 74, after "in", second occurrence, insert -- in --; column 19, line 31, for "section" read -- sections --; column 21, line 9, after "116" insert -- still --; line 27, for "lowerig" read -- lowering --; same column 21, line 60, for "strings" read -- string --; column 28, line 10, for "member", first occurrence, read -- number --; line 15, for "carbon" read -- carton --.

Signed and sealed this 23rd day of May 1961.
